UNITED STATES PATENT OFFICE.

THOMAS E. McLAUGHLIN AND MICHAEL C. McLAUGHLIN, OF HOLBROOK, MASSACHUSETTS.

SHOE-SEWING MACHINE.

Application filed March 6, 1924. Serial No. 697,342.

Our invention relates to shoe sewing machines and more especially to needle-feed machines of the type used for sewing the shoe parts to the sole in "stitch-down" shoes, so called.

The objects of our invention are to provide a new and useful presser-foot and its co-operating needle plate or table whereby the sewing operation is facilitated by eliminating the operations of molding and tacking, and the machine otherwise improved in the manner hereinafter fully set forth.

With these objects in view our invention comprises a presser-foot, the salient feature of which is a knob-shaped or rounded downwardly-bulging toe, having its inner or operative face located forwardly of the needle and arranged to engage the upper, vamp, box or counter, or whatever shoe part is to be sewed to the sole, and press the same against the last as the shoe is fed through the machine, together with a co-operating table having a lateral extension offset from its supporting shank toward the needle and slightly inclined from its forward to its rearward end so as to hold the work tight to the shoe while tension is being put on the stitches, said lateral extension having a needle slot terminating in a groove at its rearward end and being extremely narrow so as to enable the operator to tip the shoe during the sewing operation to a greater extent than is possible with tables of the prior art.

One embodiment of our invention which has proven efficient in practice is shown in the accompanying drawings, but it is to be understood that various modifications may be made in the particular form selected for illustration without departing from the scope of our invention, as set forth in the appended claim.

In the drawings—

Figure 1 is a side view of a presser-foot and its co-operating needle-plate or table;

Fig. 2 is a front view of said presser-foot and table;

Fig. 3 is a plan view of the presser foot;

Fig. 4 is a vertical section of the table;

Fig. 5 is a plan view of the table;

Fig. 6 is a rear elevation of the presser foot.

In the particular drawings selected to more fully illustrate my invention 10 represents a presser foot extending laterally and forwardly from its shank 11 which is secured to the presser-foot bar 12 by any suitable

means herein illustrated as a clamp integral with said shank and formed by splitting the socket 13 in the upper end thereof and providing said upper end with two lugs 14 with which the screw 15 has threaded engagement. 60 The surface of the bottom portion 16 of the presser foot is substantially flat and terminates forwardly, i. e., in front of the needle 17 mounted in the needle bar 18, in a rounded downwardly-bulging toe 19, the inner or operative face 20 of said toe being curved from the point of the toe toward the last as the shoe is fed through the machine and being therefore arranged to engage the upper or other shoe part which is to be sewed to the sole and 70 press the same against the last during the sewing process.

By means of our improved presser foot the upper is held tight to the last by the clamping action of the inner face 20 of the presser foot 75 and the operations of molding and tacking as ordinarily performed are eliminated. Furthermore by means of our improvement it is possible to stitch boxes and counters to the sole as well as the other shoe parts. 80

While any suitable needle-plate or table may be used with the presser foot above described, we prefer to employ the table shown in the lower part of Figs. 1 and 2, said table having a shank 21 secured to an upright 85 bracket 22 and provided with a lateral extension 23 offset from said shank by being mounted on the portion 24 which is inclined toward the needle.

The lateral extension 23 which constitutes 90 the table proper is extremely narrow and is rounded at its outer edge as shown at 25. The table is provided with a needle-slot 26 terminating at its rearward end in a groove 27 which is deep enough to accommodate the 95 stitch. Preferably the table is inclined from front to rear as shown in Fig. 1 so as to hold the work tight while tension is being put on the stitches.

By making the table as narrow as the 100 strength of the material will permit, and placing the needle-slot very near its outer edge, the operator is enabled to tip the shoe during the sewing operation to a greater extent than was heretofore possible, and furthermore this permits stitching on a high-shank, as well as on a low-shank, last.

By virtue of our improved presser foot and table it is possible to give a stitch-down shoe the appearance of a Goodyear welt shoe, and 110

to reduce the lateral extension of the sole and the out-turned portion of the upper which is stitched thereto, thereby making a much neater looking stitch-down shoe than was possible by the machines of the prior art.

Having thus described an illustrative embodiment of our invention without however limiting the same thereto, what we claim and desire to secure by Letters Patent is:—

10 In a shoe sewing machine, a needle-plate or table having a shank and a lateral extension offset from said shank toward the needle and

inclined rearwardly, said lateral extension having a longitudinally-extending needle slot passing vertically therethrough and a horizontal thread groove formed in its upper surface, said thread groove intersecting said slot at the rearward end of the latter.

In testimony whereof, we have hereunto subscribed our names this 7th day of February, 1924.

THOMAS E. McLAUGHLIN.
MICHAEL C. McLAUGHLIN.
